UNITED STATES PATENT OFFICE.

JOSEPH O. THERIEN, OF MINNEAPOLIS, MINNESOTA.

BUSH-HAMMER.

SPECIFICATION forming part of Letters Patent No. 425,153, dated April 8, 1890.

Application filed February 8, 1890. Serial No. 339,660. (No model.)

To all whom it may concern:

Be it known that I, JOSEPH O. THERIEN, a citizen of the United States, residing at Minneapolis, in the county of Hennepin and State of Minnesota, have invented new and useful Improvements in Bush-Hammers, of which the following is a specification.

This invention relates to that type of instruments known as "bush-hammers" for dressing stone, wherein a series of blades or cutters are clamped between metallic plates and about a head or poll piece formed separate from and on which the clamp-plates are bolted.

15 The objects of my invention are to improve the prior devices and provide a strong, durable, and efficient bush-hammer in which the clamp-plates are centrally mounted on bosses which project from the center of the head or poll.

20 The invention consists in the features of construction and the combination or arrangement of parts hereinafter described in detail, and specifically set forth in the claim, reference being made to the accompanying drawings, in which—

25 Figure 1 is a perspective view of the improved bush-hammer. Fig. 2 is a similar view showing the head or poll and the clamp-plates separated from each other, and Fig. 3 is a longitudinal sectional view of the hammer.

In order to enable those skilled in the art to make and use my invention, I will now describe the same in detail, referring to the drawings, wherein—

30 The numeral 1 indicates the rectangular head or poll piece formed integral at the center of each side with a cylindrical boss 2, these two bosses being in line and projecting laterally in opposite direction from the head or poll piece. The two sets of cutters or blades

35 respectively about opposite edges of the head or poll piece and are of the ordinary construction. The rectangular clamp-plates 4 are each formed at its center with a circular orifice 5, 45 extending therethrough to receive within it one of the cylindrical bosses, the latter being of a length co-extensive with the thickness of the clamp-plates, so that the parts are flush, as shown in Fig. 3. The clamp-plates are 50 provided at each end portion with a series of bolt-holes 6 for the passage of bolts 7, to which are applied nuts 8. The bolts extend through both clamp-plates and through the cutters or blades, and by tightening the nuts 55 the several parts are all firmly united and a rigid structure produced which provides a substantial, durable, and efficient bush-hammer for dressing stone.

I have shown the bosses cylindrical and the 60 orifices in the clamp-plates circular; but I do not confine myself to this precise shape.

The eye 9 for the usual handle extends through the head or poll piece between the 65 two bosses.

Having thus described my invention, what I claim is—

A bush-hammer consisting of the head or poll piece provided with two integral bosses 70 extending laterally from the center in opposite directions, the clamp-plates, each having centrally between its longitudinal edges an orifice which receives a boss, the cutters or blades, and the clamp-bolts, substantially as described.

75 In testimony whereof I have affixed my signature in presence of two witnesses.

JOSEPH O. THERIEN.
